United States Patent Office

Des. 187,830
Patented May 3, 1960

187,830

LETTER TRAY

Donald F. Lewis, Golden, Colo., assignor of one-half to Peter Pepper Products, Inc., Lomita, Calif., a corporation of California

Application April 27, 1959, Serial No. 55,675

Term of patent 14 years

(Cl. D74—9)

Fig. 1 is a top perspective view of a letter tray showing my new design;

Fig. 2 is a front elevational view; and

Fig. 3 is a bottom perspective view thereof.

I claim:

The ornamental design for a letter tray, substantially as shown.
